UNITED STATES PATENT OFFICE.

HERMAN FORCE, OF MONTROSE, NEW YORK.

DESIGN FOR A SHELF-COVER.

SPECIFICATION forming part of Design No. 13,331, dated October 10, 1882.

Application filed August 19, 1882. Term of patent 14 years.

To all whom it may concern:

Be it known that I, HERMAN FORCE, a citizen of the United States, residing in Montrose, Westchester county, in the State of New York, 5 have invented certain new and useful Improvements in Designs for Shelf-Covers, fully described and represented in the following specification and the accompanying drawings, forming a part of the same.

10 My design is intended for use upon the enameled oil-cloth covers made and sold for use upon shelves and mantels; and it consists in the combination shown in the annexed drawing.

15 A is such a shelf-cover. B is the border provided with my design; and C is a shelf, upon which the cover is represented as lying, with the border overhanging the edge.

20 The design relates entirely to the overhanging border, and consists in an ornamental pattern, a, near the edge, an edge pattern, b, and an indented margin, c, intersecting the pattern b irregularly.

25 Shelf-covers have heretofore been made with indented edges formed by pinking, and I do not therefore claim such an edge as new; but such indented edges have been formed upon enameled cloth which was unprovided with any printed pattern along the edge, like mine.

To avoid the trouble of cutting the edge to correspond exactly with the printed pattern, I have 30 devised the design herein shown, which has a pattern of finer figures formed along the edge, which may be intersected by any kind of scalloped or indented margin without unpleasant effect. Such fine figures are not, however, 35 claimed in combination with the waved or indented margin c alone, but also with an ornamental pattern, a, between the fine pattern b and the body of the cover A.

By the use of such design the margin of the 40 covers may be cut into an ornamental shape without conforming to the printed pattern a, which is the chief ornament of the edge.

Having thus fully set forth the nature of my design, I claim the same as follows: 45

The design for the borders of enameled-cloth shelf-covers, consisting in an ornamental pattern, a, an edge pattern of finer figures, b, and an indented margin, c.

In testimony whereof I have hereunto set 50 my hand in the presence of two subscribing witnesses.

HERMAN FORCE.

Witnesses:

THOS. S. CRANE,

HENRY F. GÖKEN.
